ICE COMPARTMENT FOR REFRIGERATOR CARS

Charles L. Moerman, Chicago, Ill., assignor to
 Union Asbestos & Rubber Company, Chicago,
 Ill., a corporation of Illinois

Application August 27, 1937, Serial No. 161,216

7 Claims. (Cl. 62—19)

This invention relates to improvements in ice compartments for refrigerator cars and similar locations, and more particularly to a simplified and efficient ice compartment construction with special reference to an improved bulkhead assembly and an improved grate construction, although the invention may have other uses and purposes as will be apparent to one skilled in the art.

10. The present invention is an improvement over the structure set forth and claimed in my co-pending application for patent entitled "Ice compartment for refrigerator car," filed October 21, 1935, Serial No. 45,847.

15. In the manufacture of refrigerator cars, it is not only desirable to have an economical, simply constructed and readily installed refrigerator compartment, but it is also desirable to have a bulkhead assembly arranged to provide a maximum amount of cooling surface together with a great amount of ventilation, so that circulating air may not only pass over the bulkhead but directly through the bulkhead assembly. It is also desirable to have a strong grate consistent 20 with lightness of material, and to have the grate so proportioned that adequate ventilation through it is obtainable, regardless of the packing of the refrigerant used. With both the grate assembly and bulkhead assembly designed for the passage 25 therethrough of circulating air, air may circulate through the grate and the bulkhead assembly in a continuous movement, thus insuring maximum refrigerating efficiency from the particular refrigerant used. Difficulty has been experienced heretofore in providing a bulkhead having an increased radiating surface together with ventilating facilities, and also a grate construction which is not only economical and simple to install and remove, but which also has 30 adequate strength and yet permits substantially a maximum air circulation therethrough.

With the foregoing in mind, it is an important object of the present invention to provide a bulkhead assembly including a wall of the refrigerant 35 compartment shaped to provide increased cooling surface contacted by circulating air, which wall is further provided with numerous openings through which circulating air may travel.

Another object of this invention is the provision of a bulkhead assembly for a refrigerating compartment including a wall of the compartment shaped with outstanding vanes, hollow on the inside to permit the entrance into the vanes or fins of refrigerant, the vanes or fins 45 being provided with numerous apertures through

which circulating air may pass directly into contact with the refrigerant.

A further object of the invention is the provision of a bulkhead assembly including a wall of a refrigerating compartment, which wall comprises a plurality of spaced outstanding hollow fins, the fins and the wall space therebetween being provided with numerous openings through which circulating air may pass. 5

It is also an object of this invention to provide a refrigerant compartment having a novel grate construction so designed as to provide more than adequate strength and yet permit the passage of circulating air directly through the grate in a much greater quantity than with any grate construction heretofore known. 10

Another feature of the invention is to provide a refrigerant compartment including a grate construction which may be installed in relatively wide sections, each section comprising a unitary element shaped to provide a plurality of upright beam-like portions with openings therebetween, said openings extending substantially the width of the grate. 15

Still another object of the invention is the provision of a refrigerant compartment containing a grate construction made up of unitary sections, each section comprising a plurality of spaced hollow upstanding vanes each having a plurality 20 of apertures therein, with a relatively large opening extending substantially the width of the grate construction between adjacent vanes. 25

It is also a feature of this invention to provide a refrigerant compartment containing a grate 30 construction which is exceedingly economical to install, which is very durable, and which provides maximum ventilation and more than adequate strength. 35

A further object of the invention is the provision of a refrigerant compartment containing a grate construction having ventilation openings 40 therein so situated that it is practically impossible for refrigerant to become so disposed as to prevent circulating air from passing through the major portion of said openings. 45

Still a further object of the invention is the provision of a refrigerant compartment having a wall provided with numerous openings and a grate construction also provided with numerous openings, both the wall and grate construction being designed so that it is practically impossible for refrigerant to prevent circulating air from passing through at least a great number of the openings, whereby circulating air may pass in a 50 55

continuous stream through said wall and through the grate construction.

While some of the more salient features, characteristics and advantages of the present invention have been above pointed out, others will become apparent from the following disclosures, taken in conjunction with the accompanying drawings, in which:

Figure 1 is a fragmentary vertical sectional view through a refrigerator car, with parts broken away, looking towards the refrigerant compartment at one end of the car, showing a refrigerant compartment embodying principles of the present invention;

Figure 2 is a fragmentary vertical sectional view through the refrigerant compartment, taken substantially as indicated by the line II--II of Figure 1, looking in the direction indicated by the arrows;

Figure 3 is a fragmentary front elevational view of one of the panels of the bulkhead assembly;

Figure 4 is a top plan view of the structure of Figure 3;

Figure 5 is a fragmentary top plan view of the grate assembly;

Figure 6 is a fragmentary end elevational view of the structure of Figure 5;

Figure 7 is a fragmentary side elevational view of the grate construction, with certain of the adjacent parts being shown in section;

Figure 8 is a plan sectional view, taken through the bulkhead assembly, looking down upon the structure of Figure 7; and

Figure 9 is a fragmentary transverse vertical sectional view, taken substantially as indicated by the line IX--IX of Figure 8, looking in the direction of the arrows.

As shown on the drawings:

The illustrated embodiment of the present invention is shown in connection with a freight or refrigerator car of substantially any standard construction, of which the body portion of the car is illustrated.

Exclusive of external supporting means, the car includes an insulated floor 10, insulated side and end walls 11 and false side and end walls 12 spaced from the walls 11 to provide an insulating dead air space therebetween. The car is also provided with a suitable roof 13 and a false insulated roof 14 extending at least over the refrigerator compartment and preferably over the entire car. A suitable hatch 15 is provided in the roof 13 communicating directly with the refrigerant compartment below the false roof 14. Of course, in most instances, the refrigerator car will be provided with a refrigerant compartment at each end thereof. Between the refrigerant compartments, there is preferably a false floor 16 elevated from the insulated floor 10 so that air may circulate freely beneath the floor 16.

Each of the refrigerant compartments preferably extends across one end of the car and is enclosed on each side by the false walls 12, on the end by a second false wall 17 which is preferably metallic and spaced from the end false wall 12 to provide a dead air insulation space, and by a bulkhead assembly which will be later more fully described herein. The refrigerant compartment may be filled through the hatch 15 with any suitable refrigerant, such as ice, for example.

When a refrigerant such as ice is used, adequate drainage means must also be provided for the elimination of melted refrigerant. With reference to Figures 1 and 2, it will be noted that the

floors 10 and 16 terminate adjacent a refrigerant compartment 18 defined as outlined above. Immediately beneath the bulkhead assembly is a supporting joist or stringer 19 shouldered to accommodate a wooden floor section 20 preferably covered by a metallic member 21. Another timber 22 aids in supporting the floor section 20, and this timber together with the floor 20 is hollowed out to receive a drain catch 23 which may be integral with the metallic covering 21. Through this catch a drain pipe 24 extends leading outside of the car as a whole, and the upper end of the pipe may be protected by a scum hood or the like 25.

The present invention centers itself more particularly in the novel refrigerant compartment 18, with special reference to the novel bulkhead assembly and the novel grate construction and their association with each other. The bulkhead assembly and grate construction are so designed that air may readily circulate directly through either of them, and if air is moving in a certain direction, it may pass through the bulkhead assembly and through the grate construction in a continuous path. In other words, with the present invention a full and complete circulation of air is provided so that the air circulating through the grate and that circulating through the bulkhead assembly are not kept separate. The arrangement of the bulkhead assembly and the grate construction is such that there will at all times be a good circulation of air through each of the parts of the refrigerant compartment, regardless of the position or disposition the refrigerant may assume while melting.

The bulkhead assembly includes a plurality of side-flanged stirrups 26 shaped to seat upon the aforesaid stringer 19. These stirrups are placed in suitable spaced relationship and each is designed to accommodate a pair of vertical channel irons disposed back to back to form a composite H-beam 27. Of course, the channel irons may be bolted or otherwise secured to the stirrups and the stirrups may be attached to the stringer in any suitable manner.

Between adjacent H-beams 27 and secured to the webs thereof in any suitable manner is a metallic section 28, a plurality of which form a front for the refrigerant compartment. As best seen in Figures 3 and 4, each of the sections 28 is provided with a plurality of outstanding substantially V-shaped vanes or fins 29. These fins are hollow so that refrigerant may enter into them, and the fins are preferably separated leaving substantially flat portions of the section therebetween. The sides of each section are formed into opposed outstanding flanges 30-30, which flanges are secured inside the confronting channels and to the webs of adjacent H-beams 27, as indicated in Figure 2. It will be noted that such construction of the sections 28 results in increased surface area for contact by circulating air passing over the front of the sections 28 between them and a suitable bulkhead 31, which may be made of wood or any other suitable material. As seen best in Figure 8, the bulkhead is preferably disposed against the outer edges of the fins 29, so that a plurality of air passages 32 are formed between adjacent fins. With reference to Figure 2, it will be seen that an imperforate baffle 33 is mounted above the sections 28 and above the bulkhead 31 to guide warm air downwardly through the passages 32. This baffle preferably slopes inwardly and is, of course, imperforate. Of course, the fins terminate below the false roof 75.

14, and the bulkhead terminates above the lower portions of the sections 28, so that air may freely circulate downwardly through the passages 32 and escape into the body portion of the car 5 through the opening between the bulkhead and the false floor 16.

It will be especially noted that not only the fins 29 but the flat portions therebetween are provided with numerous apertures or openings 34, 10 so that air may not only circulate over the sections 28 but may also pass directly through them and enter the refrigerant compartment 18. The openings 34 are so numerous as to effectively prevent clogging of more than a few of them by 15 melting refrigerant.

With reference to Figures 2 and 7, it will be seen that the stirrups 26 are provided with flanges 35 extending into the refrigerant compartment 18. Seated across these flanges is an 20 angle iron 36 which extends substantially across the refrigerant compartment, as seen in Figure 9.

Adjacent the end of the car, a plurality of upright supports 37 are provided, each of which is topped by an inverted angle iron or the equivalent 25 38, likewise extending substantially entirely across the refrigerant compartment. The angle irons 36 and 38 form a support for the novel grate construction now about to be described.

The grate construction also includes a plurality 30 of separate sections, each of which is generally indicated by numeral 39. These sections may be merely laid upon the angle irons 36, or if preferred, they may be bolted thereto or secured in any other suitable manner. It is not necessary 35 for the sections to be secured to the angle irons, because the sections interlock with each other and extend the full width of the refrigerant compartment, and even though rather large chunks of refrigerant be dropped through the 40 hatch 15 upon the grate, they cannot become disordered.

The grate sections are seen more clearly in Figures 5, 6, 7, 8 and 9. Each section is preferably stamped or otherwise formed out of metal 45 and so shaped as to provide a plurality of upstanding ridges or fins 40 extending the full length of the section. Between the upstanding ridges 40, flat spaces 41 are provided at each end of the section, these flat spaces resting upon the aforesaid angle irons 36 and 38. As best 50 seen in Figure 9, the ridges 40 extend both above and below the flat portions 41. The ridges are hollow beneath and terminate in such a manner as to provide a materially large aperture 42 extending substantially the full length of the sections between each adjacent pair of ridges. At 55 each end of the section, the lower portions of the ridges or ribs 40 merge upwardly into a flat portion 41, as indicated at 43. Besides the large 60 openings 42, each of the ribs 40 is provided with numerous apertures 44 on each side thereof, so that it is practically impossible for melting refrigerant to assume any position so as to block a flow of air through most of the openings 44 65 and through the major portions of the large openings 42.

Each grate section at one end thereof is provided with an upstanding flange 45, and at the other end with an upstanding flange having a 70 hooked top 46 whereby the various grate sections may be effectively interlocked together, as indicated at 47 in Figure 9. It is a simple expedient to lay the various grate sections 39 in position in their interlocked relationship and they will 75 remain firmly in place.

It will be noted that each grate section is relatively light and yet so formed as to have more than adequate strength, while permitting greatly increased air circulation therethrough over anything known heretofore. The grate as a whole 5 is elevated above the metallic flooring element 21 so that there is ample room for air circulation beneath the grate. The air may circulate downwardly through the passages 32, inwardly through the openings 34, down through the grate sections 10 themselves, so that air may pass at any time in a continuous path through both the grate structure and the bulkhead assembly. With such construction, adequate use is made of the cool air at the bottom of the refrigerant compartment, 15 and this cool air is not permitted to merely remain idle at the bottom of the refrigerant compartment, but is circulated as an aid in keeping the contents of the car in a satisfactory 20 refrigerated condition.

It is further apparent that my novel refrigerant compartment, with special reference to the grate structure and bulkhead assembly, may be very easily installed and is extremely economical, yet possessed of more than ample strength and 25 durability.

I am aware that many changes may be made and numerous details of construction may be varied through a wide range without departing from the principles of this invention, and I, 30 therefore, do not propose limiting the patent granted hereon otherwise than is necessitated by the prior art.

I claim as my invention:

1. In a refrigerating car, walls defining a 35 refrigerant compartment, one of said walls being of material of higher heat conductivity than the other walls and having a plurality of hollow vertically extending fins, said fins being provided with numerous perforations, and a bulkhead disposed against the outer ends of said fins to provide air passages, the space between the bulkhead and said wall being open both at the top and bottom thereof, and means arranged to guide circulating air between said wall and the 40 bulkhead.

2. In a refrigerating car, means defining a 45 refrigerant compartment including a wall having a plurality of spaced hollow fins extending outwardly therefrom, said fins being provided with 50 numerous apertures as well as said wall between the fins, and a bulkhead disposed against the outer edges of said fins, and a baffle to guide circulating air between the wall and bulkhead.

3. In a refrigerator car, means defining a 55 refrigerator compartment, grate supports, a grate in said compartment including a plurality of grate sections each freely carried by said supports and shaped to provide upstanding ribs with a relatively large opening between adjacent 60 ribs, said ribs each having numerous apertures therein, and complementary formations carried by said sections for interlocking engagement.

4. In a refrigerator car, means defining a 65 refrigerant compartment, a grate in said compartment including a grate section having a flat portion at each side thereof for engagement with supports, and said section being shaped to provide a plurality of spaced upstanding ribs with an elongated opening between adjacent ribs, 70 said ribs extending above and below said flat portions, and said ribs being hollow and provided with numerous openings in the side walls thereof.

5. In a refrigerator car, means defining a 75

- refrigerant compartment, a grate in said compartment including a grate section shaped to provide a plurality of spaced hollow upstanding ribs open underneath and closed at the top and 5 each having numerous apertures in the upper part thereof, and a bulkhead assembly including a wall of tortuous configuration having numerous openings therein to permit a circulation of air in a continuous path through said grate and 10 said wall.
6. In a refrigerator unit, means defining a refrigerant compartment, supports along opposed sides of said compartment, a grate in said compartment including a plurality of grate sections 15 each having a portion at each side thereof to loosely rest on said supports, each said section being shaped to provide a plurality of spaced hollow ribs closed at the tops and having numerous openings in the side walls thereof, there

being an elongated opening between adjacent ribs, and said sections having complemental formations thereon for interlocking association each with the one adjacent.

7. In a refrigerator car, means defining a 5 refrigerant compartment, grate supports, a grate in said compartment including a plurality of grate sections each freely carried by said supports and shaped to provide upstanding ribs with a relatively large opening between adjacent ribs, 10 said ribs each having numerous apertures therein, and complemental formations carried by said sections for interlocking engagement, said sections being sized in keeping with the compartment so that a plurality of said sections will properly 15 cover the compartment between the side walls thereof.

CHARLES L. MOORMAN.
